UNITED STATES PATENT OFFICE.

LYNN T. LEET, OF MONTREAL, QUEBEC, CANADA.

LIQUID-VENDING MACHINE.

Application filed April 29, 1926. Serial No. 105,518.

This invention relates to new and useful improvements in vending machines, and particularly to devices for vending liquid, and the object of the invention is to provide a simple and easily operated machine which will dispense a predetermined quantity of fluid and place same in a cup ready for withdrawal from the machine by the vendee or operator.

Another object is to provide a vending machine in which the liquid will be properly mixed during the operation of the machine and before the liquid is measured or discharged therefrom.

A further object is to provide a machine which will be unlocked by the insertion of a coin and all motions within the machine will be controlled by the movement of a single handle by the operator.

A further object is to provide means to prevent insertion of a coin into the machine once the supply of liquid receiving receptacles or cups has become exhausted.

A further object is to provide means to receive the empty cups and to hold same in stacked formation and to release said stack of cups when they have reached a predetermined weight.

A still further object is to provide means within the machine which will allow the operating handle to be turned without moving the vending mechanism or damaging same should any person attempt to operate the machine before inserting his or her coin.

In my invention I provide a casing of substantially rectangular form with a horizontal partition dividing the casing into upper and lower compartments. The lower compartment is adapted to receive empty cups in stacked form through chutes formed in the sides of the upper compartment. The upper compartment is divided into two separate chambers, the one at the rear being properly insulated and adapted to hold a quantity of liquid. A cover may be provided for the rear chamber. The front chamber is adapted to receive the cup release controlling mechanism, the cup placing mechanism, and the coin controlled operating mechanism, which is also adapted to operate through suitable gearing a liquid agitating and measuring means within the rear chamber. Means are also provided by the movement of the cups to release a coin slot closing medium when a predetermined number of the cups have been discharged from the upper chamber of the machine.

In the drawings which illustrate one form of my invention;

Figure 1 is a perspective view of the machine showing the front chamber.

Figure 2 is a front elevation of the machine showing the liquid agitating and measuring means, the position of the operating mechanism therefor, and also the cup releasing and placing mechanism.

Figure 3 is a side elevation of the device shown in Figure 2.

Figure 4 is a front elevation of the coin controlled mechanism for operating all parts of the machine in unison.

Figure 5 is a side elevation of the mechanism shown in Figure 4.

Figure 6 is a plan of the coin receiving mechanism.

Figure 7 is a detailed plan of the cup placing mechanism.

Figure 8 is a detailed plan of the cup releasing device and operating mechanism therefor.

Figure 9 is a front elevation of the cup releasing and cup placing mechanism.

Figure 10 is a front elevation of the agitating and measuring wheel.

Figure 11 is a side elevation of the device shown in Figure 9.

Referring more particularly to the drawings, 11 designates a casing of substantially rectangular cross section and of a height suitable for easy operation of the mechanism contained therein and hereinafter described. 90

The casing is divided into two compartments 12 and 13, by the horizontally disposed partition 14. Formed in the front side walls 15 of the upper compartment are a pair of apertures 16, which communicate with vertically disposed circular chutes 17, the lower end of which communicates with the lower compartment 13. Spring fingers 18 may be attached to the lower end of said chutes to hold the used cups placed through apertures

16, in stacked form within the chute until their weight forces the springs apart and allow the stack of cups to fall into the lower compartment. A suitable hinged door 19 may be provided for the lower compartment.

The upper compartment is divided by a vertically disposed partition 20 into two chambers 21 and 22. The chamber 21 at the rear, is open at the top and may be provided with double walls between which insulation 23,

such as cork may be placed to protect the fluid from being affected by changes in tem-

perature of the surrounding atmosphere. The chamber 21 is provided with a removable cover 24 and between said cover and the edge 25 a sealing or packing medium may be placed to prevent any foreign matter from entering the said chamber. Extending from back to front of the chamber 21 is a spindle 26 to which is secured the agitating wheel 27 which also carries rotatably mounted on a projection 28, a measuring bucket 29. The wheel 27 carries a series of projecting paddles 30 which agitate the fluid in the chamber 21 so that the fruit pulp will be thoroughly mixed. The edge of the agitating wheel 15 is provided with a plurality of teeth 31, gearing with a toothed pinion 32 secured to a shaft 33 which is driven by means herein-after described. Secured to the measuring bucket is the pinion 34 which engages with 20 a curved rack 35 secured by any suitable means to the sides of the chamber and near the top thereof. The bucket is revolved and discharges the fluid contained therein into a trough 36, having an outlet pipe 37 passing 25 through the side of the chamber 21 in close proximity to the cup delivery mechanism designated as a whole by the numeral 38. A liquid trap 39 may be provided in the pipe 37 to prevent escape of the cold air within 30 the chamber. The liquid within the tank is kept cold by means of a block of dry refrigerant supported on a bracket 40 secured to the walls and within the chamber 21. The cover for the chamber is drawn down on to 35 the top of the frame by means of the pivotally mounted levers 41, the lower ends of which are provided with slots 42 passing over the eye bolts 43 secured to the outer wall of the casing and through which suitable locking means such as padlocks, not shown, 40 may be placed to lock the levers in position. This is only illustrative of one form of locking means for the cover and it will be understood that any of the well known types of refrigerator locking means may be employed. 45 The chamber 22 is provided with a hinged door 44 and positioned near the lower edge of said door a small opening 45 is formed and this opening may be closed by means of 50 a transparent hinged door 46. Positioned centrally of the chamber is the cup reservoir 47 which may extend beyond the top of the casing. Positioned at the lowermost edge of the reservoir 47 is the cup delivery controlling mechanism 48 which consists of mechanism, not shown in detail, but so operated by the horizontal movement of the lever 49 that only one cup is delivered from one complete cycle of movements of the lever, that is 55 one forward and one backward movement. The detail of this mechanism is not shown as it is well known in the vending art and any of the well known types of cup delivery mechanism may be employed. Positioned to 60 one side 50 of the chamber 22 and secured to 65 the front wall thereof is the coin controlled mechanism designated as a whole by the letter C in Figure 1 and shown in detail in Figures 4, 5 and 6. The coin controlled mechanism is mounted on the spindle 51 and 70 consists of a pair of spaced discs 52, the edges of which are each provided with one tooth 53. The discs are loosely mounted on the spindle 51 and secured to the spindle between the discs is the coin receiving element 75 54 which is adapted to receive a coin 55 in the recess formed therein and hold said coin until it contacts with a pin 56 secured to a pawl 56 engaging with the teeth 53 and rotatably suspended from a pin 57 secured to 80 the cheek plates 58. The coin is held in such a position that its edge will engage with pin 56 and raise the pawl clear of the teeth and allow the discs and spindle to be revolved in the direction indicated by arrow X. As 85 will be seen this movement of unlocking the pawl necessitates a certain amount of free movement between the pawl and said discs and this may be accomplished in the manner shown. The key 63 holding the element 54 90 to the shaft is somewhat smaller than the recess 59 formed in the wall of the bore of the discs, so that the element will have to move through a predetermined angle before movement of the discs is made. To prevent movement in the opposite direction to the arrow X a ratchet toothed wheel 60 is provided and secured to one of the discs. The teeth of the ratchet engage with the end 61 of a 95 rotatably suspended pawl 62 and tension spring 63 may be placed between the pawl 62 and the pawl 56 to hold them in engagement with their respective teeth. A coin chute 63a is provided to guide the coin so that it will fall between the discs and to the coin receiving element. A circular opening 64 is formed in the wall of the casing and the frame 64a to allow the coin to be deposited in 100 said chute. The discs, ratchet and coin receiving pawl are positioned between the frame 64a and the bracket 65 secured thereto. The spindle 51 extends beyond the bracket 65 and may be supported on the plate 66 forming part of the frame. Secured to the spindle 51 and in proximity to the 105 plate 66 is the toothed wheel 67, the teeth of which engage with the teeth of pinion 68 secured to the control shaft 69 rotatably mounted in the frame and passing through the face of the casing forming an extension 70 to which may be attached the operating handle 71. The pinion 68 is positioned between a collar 72 secured to the shaft 69 and a friction washer 73 which is pressed against the adjacent side of the pinion by the nut 74 which may be locked in position by the lock nuts 75. The pinion it will be seen, is so mounted that it may be revolved with the shaft but should the pressure exceed a predetermined amount or should the locking 110 115 120 125 130

pawls be in the locking position, the handle may be revolved without turning the pinion. Rotatably mounted on the spindle 51 between the bracket 65 and the toothed wheel 67 is the sleeve 76, to the one end of which is attached a tooth wheel 78, which is adapted to rotate the shaft 33 through the medium of the toothed pinion 79. The end of the shaft 33 nearest the front of the casing is rotatably supported in a bearing 80 suspended from bolts 81 passing from side to side of the frame. It will be seen that there must be a certain amount of free movement between the wheel 78 and the wheel 67 so that the device may be unlocked before motion is transmitted to the agitating and measuring means. This is accomplished by placing or forming a projection 82 on the wheel 67 and a projection 83 on the wheel 78, and positioning them so that wheel 67 moves through a predetermined angle before the projections come in contact, after which both wheels move in unison. Two cams 84 and 85 are formed on or secured to the sleeve. One of the cams 84 engages with a lever 86 pivotally secured at one end 87 to a pin 88 secured to the frame. Suspended from the other end is the rod 89 which may be secured to one arm 90 of a bell crank lever 92 the other arm of which is slotted and secured to the lever 49. A compression spring 91 may be mounted between the end of the rod 89 and the end 87^a of the lever 86. The rotating movement of the cam is such that it will raise the lever 86 which pulls the rod 89 upwardly, moving the bell crank lever 92 about its pivot 94, said lever in turn operating the lever 49 to release one cup from the cup reservoir. The released cup falls into a receiving arm 93 which comprises a pair of curved spring clips or supports 94 spaced at their free ends to allow the cup to be withdrawn therefrom. The cup used is tapered from top to bottom so that it will pass freely between the supports 94 with its upper edge resting on the upper edge of the supports. The arm is pivotally mounted on a pin 95 and is provided with a portion 96 extending beyond the pivot and to which is attached a connecting rod 97, the other end of which is attached to one end 98 of a bell crank lever 99 pivotally mounted on a pin 100 securing it to the casing of the machine. The other end 101 of the lever 99 is secured to a rod 102 the free end 103 of which passes through an aperture 104 formed in the free end of a lever 105, pivotally secured at one end to the pin 106 passing through the frame of the operating mechanism. This lever 105 is moved about its pivot by the movement of the cam 85 formed on or secured to the sleeve 76. A compression spring 106^a is placed between the nut 107 and the uppermost surface of the lever 105 and surrounding the rod 102. To keep the cup support beneath the cup reservoir outlet a tension spring is secured to a point in proximity to the end 101 of the lever 99, and to a pin 108 fixed to the casing of the machine. The spring draws the lever 99 against a stop 109 to limit the movement of 70 the cup receiving arm. To prevent insertion of a coin into the machine a disc 110 is moved into a position covering the coin slot opening when the last cup has been delivered from the machine, or when a predetermined number of cups have been delivered. This is accomplished by means of the last cup within the cup holding cylinder which when it passes a projection 112 of a bell crank lever 113 pivotally secured to the cup reservoir allows 80 the disc 111 to drop over the coin opening. The projection 112 passes through a slot 114 cut in the wall of the cylinder or cup reservoir and is prevented from movement by the lips of the cups. The bell crank lever 113 is 85 attached to one end 113^a of another bell crank 115 pivotally mounted on a pin 115^a passing through a bracket 116 secured to the operating gear frame. The disc 111 is pivotally suspended from the other end 117 of the lever 115 and is so positioned that it falls through a slot 118 in the top, of the coin chute and covers the coin inlet. A numbering device 120 is secured to the frame and is operated by a slotted link 119 suspended from one of 90 the levers for operating the cup releasing gear. The slotted link is secured to said lever and is adapted to move the operating pin of the numbering device every time a cup is released from its reservoir. The cup receiving support is mounted within a casing 121 the lower end of which may be tapered towards an outlet or drainage opening 122 which communicates with the interior of the lower compartment. A drain valve 123 of 100 the lift type may be provided at the bottom of the liquid reservoir to allow the liquid to be drained therefrom into the lower compartment when so desired. The valve seat 124 of the drain valve 123 is preferably placed 105 or formed in the bottom of the liquid reservoir.

Modifications may be made without departing from the spirit of the invention.

The operation of the device is as follows. 115 A coin is dropped into the machine and it drops through the chute on to the coin receiving pawl between the locking discs. The handle is then revolved and moves the shaft to which the coin receiving pawl is attached. 120 The coin raises the locking pawl and allows the shaft to be revolved through 360°, the handle in the present illustration being rotated through approximately three revolutions to accomplish this object, as the gear reduction between the handle shaft and the coin receiving pawl shaft is in the ratio of 3 to 1. The ratchet and engaging pawl prevents return of the handle or movement of same in the opposite direction to that shown 125 130

in the drawing. The toothed wheel secured to the coin receiving pawl shaft moves through a predetermined distance before it contacts with the wheel secured to the sleeve 5 on said shaft. The wheel on the sleeve rotates the agitating wheel in the liquid reservoir, which also carries a bucket which fills with liquid and when the tooth pinion attached to said bucket comes in contact with 10 the rack in the reservoir it tips the bucket, the contents of which are discharged into the trough which leads to an outlet in the side of the liquid reservoir in close proximity to the cup reservoir. While the sleeve is rotating 15 the cams therein first release a cup from the reservoir to fall on to the cup holder which is swung about its pivot so that the released cup is placed beneath the outlet to receive the liquid. A bell 125 supported on the 20 frame may be rung by means of a spring hammer 126 which may be operated by a projection 127 secured to the sleeve so that the operator will be warned that the cup is filled and may be withdrawn from the machine 25 through the door provided for that purpose. When the stack of cups becomes exhausted, the coin slot is closed by a disc. The used cups may be placed in the slots at the side of the casing and are supported in stacked formation 30 at the bottom of the empty cup chute until they weigh a certain amount which overcomes the resistance of the spring and allows the stack of empty cups to fall into the compartment at the bottom of the casing. The 35 coin falls into a receptacle 129 when released from engagement with the coin receiving pawl and the disc pawl. A chute 130 may be provided to guide the coin towards said receptacle 129. It will be seen that the device 40 is very simple to operate and provides a

liquid vending machine which keeps the liquid cool and the pulp within the liquid properly mixed therewith. The liquid is measured and delivered into a cup or receptacle which may be withdrawn from the machine and when emptied may be placed within the lower compartment of the machine, so that no empty cups are left lying around the base of the machine. The machine cannot be operated until a coin of the proper value 45 is inserted therein and provision is made to allow the handle to be rotated so that the operating mechanism cannot be injured by malicious or mischievous persons. 50

Having thus described my invention, what 55 I claim is:—

1. In a liquid vending machine, a sealed liquid reservoir, an agitating wheel rotatably mounted in said reservoir, paddles extending from the side of the wheel, a measuring bucket rotatably mounted on the side of the wheel, a toothed pinion secured to the bucket, a rack secured to the interior of the reservoir and adapted to contact with the toothed pinion to rotate the bucket through one complete revolution and means to rotate said agitating wheel. 60

2. A liquid vending machine comprising a liquid reservoir, a vertically disposed wheel rotatably mounted in said reservoir, liquid 70 agitating paddles projecting laterally from said wheel, a measuring bucket rotatably mounted on one side of said wheel, and means for causing said bucket to make a complete revolution about its mounting at a predetermined point in the revolution of the wheel. 75

In witness whereof, I have hereunto set my hand.

LYNN T. LEET.
